United States Patent Office

Des. 185,401
Patented June 2, 1959

185,401

FLOOR POLISHER

Edward L. Verhagen, Rahway, N.J.

Application December 22, 1958, Serial No. 53,857

Term of patent 14 years

(Cl. D9—2)

I claim:

The ornamental design for a floor polisher, as shown.
